(57) **CLAIM**

The ornamental design for a bottle, as shown and described.

DESCRIPTION

FIG. 1 is a perspective view of the bottle, embodying the new design;

FIG. 2 is a front view thereof;

FIG. 3 is a cross-sectional view taken along line 3-3 in FIG. 2;

FIG. 4 is a cross-sectional view taken along line 4-4 in FIG. 2;

FIG. 5 is a back view thereof;

FIG. 6 is a left view thereof;

FIG. 7 is a right view thereof;

FIG. 8 is a top view thereof;

FIG. 9 is a bottom view thereof;

FIG. 10 is a perspective view of the bottle, embodying the new design;

FIG. 11 is a front view thereof;

FIG. 12 is a cross-sectional view taken along line 12-12 in FIG. 11;

FIG. 13 is a cross-sectional view taken along line 13-13 in FIG. 11;

FIG. 14 is a back view thereof;

FIG. 15 is a left view thereof;

FIG. 16 is a right view thereof;

FIG. 17 is a top view thereof; and,

FIG. 18 is a bottom view thereof.

The broken lines shown illustrate portions of the bottle that form no part of the claimed design.

The oblique lines used in the drawings represent contours only and not any special material or property.

1 Claim, 8 Drawing Sheets
